UNITED STATES PATENT OFFICE.

ULYSSES G. MASON, OF BIRMINGHAM, ALABAMA.

GARMENT SUPPORT.

Application filed March 19, 1928. Serial No. 262,836.

My invention relates to a garment support, such as for trousers or skirts, and has for its object the provision of a device of the character designated which shall be adapted to hold such a garment in proper relation with a shirt or shirt waist.

A more particular object of my invention is to provide a device of the character designated which shall be adapted to hold a shirt or shirt waist down and trousers or skirt in their proper position with relation thereto.

Briefly, my invention comprises a member having a suitable clasp readily attachable to and detachable from the front of a shirt or shirt waist and a depending element adapted to engage with a belt or other supporting element of the trousers or skirt.

Apparatus embodying features of my invention is illustrated in the accompanying drawing, forming a part of this application, wherein

Fig. 1 is a perspective view of my invention.

Fig. 2 is a sectional view taken along the line II—II of Fig. 1 and showing the device engaged with the garment of the wearer; and

Figs. 3 and 4 are similar views showing a modified form of my invention.

Referring to the drawing, particularly to Figs. 1 and 2, my invention may comprise a one piece metal member having an upper clasp portion 10 and a lower hook portion 11. The clasp portion 10 is formed by bending the metal over from one side against itself so as to receive the folds of a shirt or shirt waist 12. In order that the shirt or shirt waist may be firmly held by the clasp portion, I provide corrugations 13 for the clasp, preferably on the rear portion thereof so as to leave the front clear to provide a place for a monogram 14.

The lower hook portion 11 of the device is

formed by bending upwardly the lower end 45 thereof as at 16 so as to accommodate a belt or strap 17 for holding the garment up.

Referring now to Figs. 3 and 4, I show a modified form of my invention wherein there is provided a clasp portion 21 similar to the 50 clasp portion 10, already described, and provided with a lower slot 22 to accommodate a hinge 23 which may be made of metal or fabric as desired and which is coupled, at its other end, with a hook portion 24 separate 55 from the clasp portion 21 and provided with a similar slot 26 to accommodate the hinge 23. The hook 24 is similar in all other details to the hook portion 11 of the device shown in Figs. 1 and 2.

While I have shown my invention in but two forms, it will be obvious to those skilled in the art that it is not so limited, but is susceptible of various other changes and modifications, without departing from the 65 spirit thereof, and I desire, therefore, that only such limitations shall be placed thereupon as are imposed by the prior art or as are specifically set forth in the appended claims.

What I claim is:—

1. A garment support comprising an upper clasp member formed of sheet metal having one side thereof bent around against the front portion and having said side corrugated the better to grip an upper garment, the front side of said clasp member being formed to have a monogram applied thereto, and a lower hook member formed of sheet metal bent rearwardly and upwardly to 80 engage a supporting element on a lower garment.

2. A device as set forth in claim 1 wherein in a hinge is provided between the clasp member and the hook member.

In testimony whereof I affix my signature.

ULYSSES G. MASON.
